UNITED STATES PATENT OFFICE.

THOMAS E. CLARK AND ERVING A. LUEKY, OF DETROIT, MICHIGAN.

CIRCUIT-CONTROLLING DEVICE.

1,236,543.

Specification of Letters Patent. Patented Aug. 14, 1917.

Application filed December 27, 1915. Serial No. 68,665.

To all whom it may concern:

Be it known that we, THOMAS E. CLARK and ERVING A. LUEKY, citizens of the United States, and residents of Detroit, in the county of Wayne and State of Michigan, have invented a new and Improved Circuit-Controlling Device, of which the following is a specification.

The present invention has reference to means for intermittently opening and closing a main electric working circuit, and among its important features are the following: a controlling circuit for the working circuit and means whereby the presence of current in the controlling circuit is utilized to cause one step of the intermittent action while gravity is allowed to bring about the other; means whereby the relative time devoted to each step may be readily controlled; means whereby the closing of the working circuit is insured upon the failure of the controlling means to operate; a controlling means of the nature stated comprising a circuit closer, means tending to break the circuit at the closer, gravity means for making the circuit at the closer and electro-magnetic means for retaining the circuit closed after it has been made by the gravity means; also (in combination with the elements mentioned in the last clause) electro-magnetic means for removing the gravity means from operative relation to the circuit closer, and for later deenergizing the first mentioned electro-magnetic means to allow the circuit at the closer to be broken; also means for controlling the speed of movement of the gravity means; a circuit closer for the working circuit arranged to be moved in one direction by gravity and in the other direction by current which flows through the controlling means to make or break the working circuit. The invention also consists in the details of construction shown, described and claimed.

45 The drawing is a part diagrammatic vertical section, part diagrammatic elevation of a preferred embodiment of the invention.

In the embodiment shown, 1 and 2 indicate line wires from which current is passed to the conductors 3 and 4 by means of the line switch 5. Also arranged to receive current from the switch are the conductors 6 and 8 that, together with the contacts 9 and 10 (preferably resilient), the circuit closing bars 11 and 12 (preferably including the

contacts 13 and 14) and the conductors 15 and 16, constitute the working circuit in which is interposed the lamps 18 (or other responsive device), the control of which is the ultimate object of the invention. The 60 bars 11 and 12 are supported on and insulated from the armature 19 of a solenoid having its winding 20 connected to the conductor 4. When the solenoid 20—19 is energized the working circuit is broken; when 65 it is deenergized the armature and bars 11—12 fall and current is passed through the lamps 18.

Leading from the winding 20 is a conductor 22 that is connected to the winding 70 23 of a second or circuit breaking solenoid, the armature 25 of which is arranged to reciprocate vertically and is attached to a piston 26 (preferably graphite) of a dash pot having its casing 28 provided at its opposite 75 ends with air controlling valves 29. Thus the speed of rise and fall of the armature may be regulated independently of each other. A conductor 30, having interposed therein a contact 31, joins the winding 23 80 with the winding 32 of a third or circuit holding solenoid, the armature 33 of which is preferably in alinement with the armature 25; and from the winding 32 a conductor 34, having interposed therein a contact 35, leads to a contact 36. The latter is so located in reference to the contact 31 as to be brought into electric communication therewith when the armature 25 reaches its upward limit of motion by a short circuiting 90 bar 38 carried by and insulated from the armature in any desired way, for example, by a bushing 39 of suitable material. The conductor 3 terminates in a contact 40 which is so located in respect to the contact 35 as 95 to be electrically connected thereto by a circuit breaking bar 41 (supported on and insulated from the armature 33) whenever the armature 25 reaches the limit of its downward movement and brings its weight 100 to bear upon the insulating bushing 42 that is secured to the bar 41. The bar is supported, however, on springs 43 which tend to force it away from the contacts 35—40 and may be guided by pins 44 about which 105 the springs extend. The bar may be provided with contacts 45 arranged to engage with the contacts 35 and 40 or may engage them directly.

It will be understood that the several sole. 110

noid windings, the dash pot casing, contacts 9—10—31—36—35—40, as well as the pins 44, are rigid with a block or plate, preferably marble, not shown. The circuits other than the working circuit may for convenience be termed "controlling circuits," but it will be understood of course that the common portions of the circuits may be replaced by separate conductors leading from the switch 5.

Operation.

Assuming that the parts are in the position shown (that is, with the bars 11—12 bridging the contacts 9—10 and the armature 25 resting on the bar 41, whereby the latter is pressed down to overcome the springs 43 and engage the contacts 35—40), and that the switch is closed, a circuit is made through the parts 4—20—22—23—30—32—34—35—45—41—45—40—3 in the order stated and back to the switch, whereby the armature 19 is raised and breaks the working circuit. Since the controlling circuit includes the windings 23 of the controlling-circuit breaking solenoid 23—25 and the winding 32 of the controlling circuit maintaining solenoid 32—33, it follows that the armature is drawn upwardly at a predetermined speed (determined by setting the upper valve 29), and that the bar 41 is prevented from rising simultaneously and is held in close engagement with the contacts 35—40 by the armature 33.

The circuit through the lamps is broken during the rising movement of the armature 25, but when the bar 38 reaches the contacts 31—36 the winding 32 is cut out of the circuit and current flows through the following elements: 4—20—22—23—30—31—38—36—34—35—45—41—45—40—3 back to the switch. The springs 43 now raise the bar 41 and break the controlling circuit, whereupon the solenoid 19—20 is deenergized and the armature 19 drops. Current then passes to the lamps or other elements 18 in an obvious manner.

The weight of the armature 25 gradually expels the air from the lower end of the dash pot casing 28, the rate being determined by the amount the lower valve 29 is opened, and the armature finally comes to rest upon the insulation 42 and forces the bar downwardly against the tension of the springs 43, whereupon the circuit first outlined is re-established. This completes one cycle of the operation, which is repeated indefinitely.

Because of the valves 29 it will be seen that the speed of rising and falling of the armature 25 may be so varied in respect to each other as to give complete control of the relative periods of activity and non-activity of the working circuit.

It is clear that many changes may be made in the details of construction without

departing from the spirit of our invention. We do not, therefore, wish to be limited except as indicated by the subjoined claims.

We claim:—

1. A working circuit including a circuit breaker having a conducting and a non-conducting position, means for controlling said circuit breaker, said controlling means including an electric circuit having a circuit breaking member, said circuit breaking member being movable between circuit-making and circuit-breaking positions, means tending at all times to move it to circuit breaking position, and movable means tending to return it to circuit-making position, said movable means being movable by gravity to return the circuit breaking member to circuit-making position, and electro-magnetic means for moving the movable means in the opposite direction. 85

2. A working circuit including a circuit breaker having a conducting and a non-conducting position, means for controlling said circuit breaker, said controlling means including an electric circuit having a circuit breaking member, said circuit breaking member being movable between circuit-making and circuit-breaking positions, means tending at all times to move it to circuit breaking position, and movable means tending to return it to circuit-making position, said movable means being movable by gravity to return the circuit breaking member to circuit-making position, electro-magnetic means for moving the movable means in the opposite direction, and electro-magnetic means for holding the circuit breaking means in the position to which it has been moved by the movable means. 100

3. A working circuit including a circuit breaker having a conducting and a non-conducting condition, means for controlling said circuit breaker, said controlling means including an electric circuit having a circuit breaking member, said circuit breaking member being movable between circuit-making and circuit-breaking positions, means tending to move it from one of the positions to the other, and movable means tending to return it to the first of the last named positions, said movable means being movable in one direction by gravity, electro-magnetic means for moving the movable means in another direction, and electro-magnetic means for holding the circuit breaking means in the position to which it has been moved by the movable means, said movable means including a short circuiting bar whereby the current may be short-circuited past the last mentioned electro-magnetic means to allow the circuit breaking member to again be moved by the first mentioned means for moving it. 115 120 125

4. A working circuit including a circuit breaker having a conducting and a non-con- 130

ducting position, means for controlling said circuit breaker, said controlling means including an electric circuit having a circuit breaking member, said circuit breaking member being movable between circuit-making and circuit-breaking positions, means tending at all times to move it to circuit breaking position, and movable means tending to return it to circuit-making position, 5 said movable means being movable by gravity to return the circuit breaking member to circuit-making position, electro-magnetic means for moving the movable means in the opposite direction, and means for controlling the speed at which the movable member 10 may be moved by gravity.

5. A working circuit including a circuit breaker having a conducting and a non-conducting position, means for controlling said circuit breaker, said controlling means including an electric circuit having a circuit breaking member, said circuit breaking member being movable between circuit-making and circuit-breaking positions, means 20 tending at all times to move it to circuit breaking position, and movable means tending to return it to circuit-making position, said movable means being movable by gravity, to return the circuit breaking member to circuit-making position, electro-magnetic means for moving the movable means in the opposite direction, and means for controlling the speed at which the movable member 25 may be moved by the electro-magnetic means.

6. A working circuit including a circuit breaker having a conducting and a non-conducting position, means for controlling said circuit breaker, said controlling means 40 including an electric circuit having a circuit breaking member, said circuit breaking member being movable between circuit-making and circuit-breaking positions, means tending to move it from one of the positions 45 to the other, and movable means tending to return it to the first of the last named positions, said movable means being movable in one direction by gravity, electro-magnetic means for moving the movable means 50 in another direction, means for independently regulating the speeds at which the movable member may be moved by gravity and by the electro-magnetic means, whereby the relative periods of activity and 55 non-activity of the working circuit may be determined.

7. A working circuit including a circuit breaker having a conducting and a non-conducting position, means for controlling said circuit breaker, said controlling means 60 including an electric circuit having a circuit breaking member, said circuit breaking member being movable between circuit-making and circuit-breaking positions, 65 means tending to move it from one of the

positions to the other, and movable means tending to return it to the first of the last named positions, said movable means being movable in one direction by gravity, electro-magnetic means for moving the movable means in another direction, electro-magnetic means for holding the circuit breaking means in the position to which it has been moved by the movable means, said movable means including a short circuiting 70 bar whereby the current may be short-circuited past the last mentioned electro-magnetic means to allow the circuit breaking member to again be moved by the first mentioned means for moving it, means for independently controlling the speeds at which the movable member may be moved by gravity and by the electro-magnetic means, whereby the relative periods of activity and 75 non-activity of the working circuit may be 80 determined.

8. A working circuit including a circuit breaker having a conducting and a non-conducting position, means for controlling said circuit breaker, said controlling means including an electric circuit having a circuit breaking member, said circuit breaking member being movable between circuit-making and circuit-breaking positions, means tending to move it from one of the positions 90 to the other, and movable means tending to return it to the first of the last named positions, said movable means being movable in one direction by gravity, electro-magnetic means for moving the movable means in another direction, electro-magnetic means for holding the circuit breaking means in the position to which it has been moved by the movable means, said movable means including a short circuiting bar 95 whereby the current may be short-circuited past the last mentioned electro-magnetic means to allow the circuit breaking member to again be moved by the first mentioned means for moving it, and means for controlling the speed at which the movable member 100 may be moved in one direction.

9. A working circuit and means for controlling the flow of current therethrough, said controlling means comprising a contact, 115 a circuit breaking bar, means tending at all times to force the bar away from the contact, electro-magnetic means comprising a member movable toward and from the circuit breaking bar, said member, when in one 120 position, forcing the bar into engagement with the contact against the means that at all times forces it away from the contact.

10. A working circuit and means for controlling the flow of current therethrough, 125 said controlling means comprising a contact, a circuit breaking bar, means normally tending to force the bar away from the contact, electro-magnetic means comprising a member movable toward and from the circuit 130

breaking bar, said member, when in one position, forcing the bar into engagement with the contact against the means that normally forces it away from the contact, electro-magnetic means for thereafter retaining the bar in engagement with the contact, and means controlled by the first mentioned electro-magnetic means whereby the last mentioned electro-magnetic means is rendered inoperative when the member is in another position.

11. A working circuit including a circuit making and breaking bar, controlling means for the bar, said controlling means comprising an electric circuit including two branches, one of the branches having a contact, a circuit breaking bar adapted to engage therewith, and electro-magnetic means for moving the bar in one direction, means tending to move the bar in the other direction, the other branch including the circuit breaking bar, a second contact, and a short-circuiting bar adapted to engage the second contact, and means for moving the short-circuiting bar, whereby the current is short circuited past the electro-magnetic means to allow the circuit breaking bar to be moved by the means which acts in opposition to the said electro-magnetic means.

12. A working circuit including a circuit making and breaking bar, controlling means for the bar, said controlling means comprising an electric circuit including two branches, one of the branches having a contact, a circuit breaking bar adapted to engage therewith, and electro-magnetic means for moving the bar in one direction, means tending to move the bar in the other direction, the other branch including the circuit breaking bar, a second contact, and a short-circuiting bar adapted to engage the second contact, and means for moving the short-circuiting bar, whereby the current is short circuited past the electro-magnetic means to allow the circuit breaking bar to be moved by the means which acts in opposition to the said electro-magnetic means, said means for moving the short circuiting bar comprising a solenoid the armature of which is arranged to rise and fall and which, when in lower position, rests upon the circuit breaking bar.

13. A working circuit including a circuit making and breaking bar, controlling means for the bar, said controlling means comprising a controlling circuit including a pair of branches through which the current alternately flows, a circuit breaking bar common to the branches, a solenoid winding common to the branches, one of the branches including a second solenoid winding, an armature corresponding to said second solenoid winding, said armature being arranged to draw the circuit breaking bar in one direction to hold the circuit closed, means tending to

open the circuit at the circuit breaking bar, an armature corresponding to the first mentioned solenoid winding, a short circuiting bar carried thereby, said armature resting on the circuit breaking bar when in one position, whereby the circuit is made through the circuit breaking bar and the second solenoid winding, said armature, when in another position, completing the circuit through the other branch, whereby the second solenoid is deenergized and whereupon the circuit breaking bar is caused to break the circuit.

14. A working circuit including a circuit breaker normally held in circuit closing position by gravity, means for moving the circuit breaker to break the circuit, said means including a solenoid, a controlling circuit for intermittently conducting current to the solenoid, said controlling circuit including a circuit breaker, means tending to hold the last mentioned circuit breaker in circuit breaking position, gravity means for overcoming the last mentioned means to establish the controlling circuit, said controlling circuit including electro-magnetic means for elevating the gravity means, and also including electro-magnetic means for maintaining the second mentioned circuit breaker in circuit maintaining position, and means whereby the movement of the gravity means by the first mentioned electro-magnetic means is utilized to break the circuit through the second mentioned electro-magnetic means, whereupon the second circuit breaker is forced into circuit breaking position.

15. A working circuit including a circuit breaker movable into either circuit-making or circuit-breaking position, means tending to move the circuit breaker to one of the positions stated, electro-magnetic means for moving it to the other position, said electro-magnetic means including a second circuit breaker movable into either circuit-making or circuit-breaking position, means tending to force the second circuit breaker into one of the positions stated, a member arranged to be moved in one direction by gravity, a second electro-magnetic means for moving the member in another direction, said member being arranged when in one position to force the second circuit breaker into the position other than that to which the second electro-magnetic means tends to force it, a third electro-magnetic means for holding the circuit breaker in the position to which the member has forced it, means whereby the movement of the member caused by the second electro-magnetic means is utilized to break the circuit through the third mentioned electro-magnetic means.

16. A working circuit including a circuit breaker movable into either circuit-making or circuit-breaking position, means tending to move the circuit breaker to one of the po-

sitions stated, electro-magnetic means for moving it to the other position, said electro-magnetic means including a second circuit breaker movable into either circuit-making or circuit-breaking position, means tending to force the second circuit breaker into one of the positions stated, a member arranged to be moved in one direction by gravity, a second electro-magnetic means for moving 10 the member in another direction, said member being arranged when in one position to force the second circuit breaker into the position other than that to which the second electro-magnetic means tends to force it, a 15 third electro-magnetic means for holding the circuit breaker in the position to which the member has forced it, means whereby the movement of the member caused by the second electro-magnetic means is utilized to 20 break the circuit through the third mentioned electro-magnetic means, and means for governing the speed of movement of the member caused by the action of gravity.

17. A working circuit including a circuit 25 breaker movable into either circuit-making or circuit-breaking position, means tending to move the circuit breaker to one of the positions stated, electro-magnetic means for

moving it to the other position, said electro-magnetic means including a second circuit breaker movable into either circuit-making or circuit-breaking position, means tending to force the second circuit breaker into one of the positions stated, a member arranged to be moved in one direction by gravity, a 30 second electro-magnetic means for moving the member in another direction, said member being arranged when in one position to force the second circuit breaker into the position other than that to which the second electro-magnetic means tends to force it, a third 35 electro-magnetic means for holding the circuit breaker in the position to which the member has forced it, means whereby the movement of the member caused by the second electro-magnetic means is utilized to break the circuit through the third mentioned electro-magnetic means, and means for governing the speed of movement of the member caused by the second electro-magnetic means. 40

45 In testimony whereof we have signed this specification.
